REFRIGERATION APPARATUS

Harold D. Shaw, Longmeadow, Mass., assignor to Westinghouse Electric & Manufacturing Company, East Pittsburgh, Pa., a corporation of Pennsylvania

Application July 15, 1939, Serial No. 284,634

10 Claims.

(Cl. 62—4)

This invention relates to mechanical refrigerating apparatus and more especially to a control for such apparatus.

One object of the invention is to provide a control which tends to maintain the interior of a refrigerator at a substantially constant temperature regardless of the temperature exterior of the refrigerator.

A further object is to provide a compensated control apparatus which is readily installed in a refrigerator of conventional design.

These and other objects are effected by my invention as will be apparent from the following description and claims taken in connection with the accompanying drawing, forming a part of this application, in which:

Fig. 1 is a schematic drawing of a mechanical refrigerator embodying the control apparatus of this invention; and,

Fig. 2 is a detailed view of a portion of the control apparatus.

Referring especially to the drawing for a detailed description of the invention, the reference numeral 10 designates a cabinet of a refrigerator having insulated walls 11 forming a food storage compartment 12. An evaporator 13 is secured in the upper portion of the cabinet 10 for cooling the same and is provided with an entrance tube 14 of relatively low heat storage capacity. The evaporator 13 is supplied with liquid refrigerant through a capillary flow impeding tube 16, which conducts the refrigerant from a condenser 17 to the entrance tube 14 of the evaporator 13. The vaporized refrigerant is withdrawn from the evaporator 13 through a suction tube 18 by a compressor 19 which forces the compressed refrigerant vapor through a conduit 21 into the condenser 17. A fan 22 draws air through the condenser 17 to cool the same. The fan 22 is driven by a motor 23 and the compressor 19 is driven by a second motor 24. The motor 24 receives electrical energy through leads 26 from a supply line 27.

A switch embodying a fixed contact element 28 and a movable contact element 29 is placed in one of the leads 26 in series with the motor 24. The contact elements 28, 29 are opened and closed by a snap-acting control device comprising a lever 31, a second lever 32, and a spring 38, forming an overcenter linkage. The lever 31 is actuated by an expandable bellows 25. As thus far described, the apparatus is old and well-known in the art.

According to the invention, the bellows 25 communicates with a vessel 30 comprising a tube 33

and a bulb 34 containing a small quantity of a volatile liquid 35. The bulb 34 is exposed to the air in the food compartment 12 or to any material in the food compartment 12, the temperature of which material is intended to be held relatively constant. A portion 36 of the tube 33 is placed in heat exchange relationship with the entrance tube 14 of the evaporator 13 through a strip of metal 37. A heater 39 and a thermostatic switch 20 for controlling the same are located adjacent the portion 36 of the tube 33, and the heater 39, the switch 20, and the portion 36 are preferably enclosed in an insulated housing 38.

The thermostatic switch 20 comprises a bimetallic blade 42, a contact element 40 thereon, and a second fixed contact element 45. The heater 39 and the thermostatic switch 20 are connected in series in a circuit comprising leads 41 connected, respectively, to the contact elements 28, 29 so that the heater is in series with the motor 24 when the contact elements 28, 29 are open and the contact elements 40, 45 are closed. When the contact elements 28, 29 are closed, the heater is short-circuited.

When the heater 39 is energized, it heats and maintains the portion 36 of the tube 33 at a temperature somewhat higher than the temperature at which the bulb 34 is maintained when the refrigerator is in operation.

The operation of the control device is as follows: Assume that the food chamber 12 has been cooled to its normal temperature, and that the contact elements 28, 29 and 40, 45 are in the open position and the volatile liquid 35 is in the bulb 34 as shown in Figs. 1 and 2. In this position, the refrigerant-supplying apparatus, including the motor 24 and the compressor 19, is not operating and the heater 39 is not energized.

Heat will gradually leak through the walls 11 of the cabinet 10 and warm the food chamber 12 in which the bulb 34 is located. As the temperature of the bulb 34 increases, the volatile liquid 35 therein vaporizes and expands the bellows 25 to close the contact elements 28, 29. The closing of the contact elements 28, 29 starts the motor 24 and initiates the supply of refrigerant to entrance tube 14 and the evaporator 13.

The vaporizing refrigerant in the tube 14 gradually cools the metal strip 37 and the portion 36 of the conduit 33 to a temperature below that of the bulb 34. The liquid 35 in the bulb 34, being warmer than the portion 36, will vaporize and condense in the portion 36 and adhere to this portion by capillary attraction. The vapor pres-

sure of the liquid, therefore, will no longer conform to the temperature of the bulb 34 but will conform to the lower temperature of the portion 36 of the tube 33. This decrease in temperature reduces the vapor pressure of the liquid, and the expansible bellows 25 will contract and open the contact elements 28, 29 thereby stopping the flow of refrigerant to the evaporator 13.

Generally before the contact elements 28, 29 have opened, the contact elements 40, 45 are closed by the bi-metallic blade 42 in response to the lower temperature prevailing in the insulated housing 38 and brought about by the heat withdrawn from the interior of the housing 38 by the metal strip 37 and the refrigerant in the tube 14. When the contact elements 40, 45 are closed under the action of the bi-metallic blade 42, and contact elements 28, 29 are opened by the decreased pressure of the liquid 35, the heater 39 is energized and quickly warms the tube portion 36 above the temperature of the bulb 34; however, in a capillary tube system, as shown, the warming time should be of sufficient duration to permit the pressure between the high and low pressure sides of the system to equalize so the motor 24 will start. The warming of the tube portion 36 vaporizes the liquid 35 therein and condenses it in the bulb 34 since the latter is now the coldest portion of the vessel 30. The bulb 34, therefore, again assumes control and will close the main contact elements 28, 29 when the temperature of the bulb 34 increases because of heat leakage through the walls 11 of the cabinet or other causes. The metal strip 37 is secured to the tube 14 in preference to the evaporator 13 because the former has a smaller heat storage capacity so that less heat is required in the heater 39 to raise the tube section 36 to the required temperature. It is also preferably connected above the normal level of the liquid refrigerant in the tube 14 where the heat storage capacity is smaller.

It will be apparent from the above that this embodiment of the invention provides a control for a mechanical refrigerator which is responsive to the temperature of the air in the refrigerator for starting the refrigerating cycle and which thereby maintains the air in the refrigerator at a substantially constant temperature. The control apparatus of this invention is also adapted for installation in refrigerators of conventional design because all the mechanical changes required are to install the control elements illustrated in Fig. 2, and to pass the wires 32 through the walls of the refrigerator to the contact elements 28, 29. In those cases where the contact elements 28, 29 are within the refrigerated cabinet 10, the passing of the wires 41 through the walls of the refrigerator is not necessary.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in

heat exchange relationship primarily with the cooling unit, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel substantially solely during the period between the stopping and the starting of the flow of refrigerant to the cooling unit to maintain the temperature of the second portion of said vessel above that of the first portion thereof during said period.

2. In a mechanical refrigerator, the combination of an insulated cabinet, a cooling unit therefor, said cooling unit having a portion of low heat storage capacity, means for supplying refrigerant to said cooling unit, and a controlling device for said means comprising a vessel having a first portion thereof in heat exchange relationship primarily with the media in said cabinet and a second portion in heat exchange relationship primarily with the portion of the cooling unit of small heat storage capacity, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel substantially solely during the period between the stopping and the starting of the flow of refrigerant to the cooling unit to maintain the temperature of the second portion of said vessel above that of the first portion thereof during said period.

3. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in heat exchange relationship primarily with the cooling unit, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel by a heat source independent of the ambient air and of said refrigerant-supplying means.

4. In a mechanical refrigerator, the combination of an insulated cabinet, a cooling unit therefor, said cooling unit having a portion of low heat storage capacity, means for supplying refrigerant to said cooling unit, and a controlling device for said means comprising a vessel having a first portion thereof in heat exchange relationship primarily with the media in said cabinet and a second portion in heat exchange relationship primarily with the portion of the cooling unit of small heat storage capacity, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel by a heat source independent of the ambient air and of said refrigerant-supplying means.

5. In a mechanical refrigerator, the combination of an insulated cabinet, a cooling unit therefor, means for supplying refrigerant to said cool-

ing unit, and a controlling device for said means comprising a vessel having a first portion thereof in heat exchange relationship primarily with the media in said cabinet and a second portion in heat exchange relationship primarily with the cooling unit, a volatile fluid in said vessel, said fluid being partially in the liquid phase, a switch responsive to the vapor pressure of said fluid for starting and stopping the flow of refrigerant from the refrigerant-supplying means to the cooling unit, and means responsive to said switch for heating the second portion of the vessel during the period between the stopping and the starting of the flow of refrigerant to the cooling unit to maintain the temperature of said second portion above that of the first portion thereof during said period.

6. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in heat exchange relationship primarily with the cooling unit, a volatile fluid in said vessel, said fluid being partially in the liquid phase, a switch comprising two contact elements responsive to the vapor pressure of said fluid for starting and stopping the flow of refrigerant from the refrigerant-supplying means to the cooling unit, and an electric heater in heat exchange relationship with said second portion and connected across said contact elements for heating the second portion of the vessel during the period between the starting and the stopping of the flow of refrigerant to the cooling unit to maintain the temperature of the second portion of said vessel above that of the first portion thereof during said period.

7. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in heat exchange relationship primarily with the cooling unit, a volatile fluid in said vessel, said fluid being partially in the liquid phase, a switch comprising two contact elements responsive to the vapor pressure of said fluid for starting and stopping the flow of refrigerant from the refrigerant-supplying means to the cooling unit, an electric heater in heat exchange relationship with said second portion and connected across said contact elements for heating the second portion of the vessel during the period between the starting and the stopping of the flow of refrigerant to the cooling unit to maintain the temperature of the second portion of said vessel

above that of the first portion thereof during said period, and a thermostat associated with said heater for limiting the temperature thereof.

8. In a mechanical refrigerator, the combination of an insulated cabinet, a cooling unit therefor, means driven by an electric motor for supplying refrigerant to said cooling unit, a controlling device for said motor comprising a vessel having a first portion thereof in heat exchange relationship primarily with the media in said cabinet, and a second portion in heat exchange relationship primarily with the cooling unit, a volatile fluid in said vessel, said fluid being partially in the liquid phase, a switch responsive to the vapor pressure of said fluid for starting and stopping said motor, an electric heater in heat exchange relationship with said second portion and connected across said switch for heating the second portion of the vessel during the period that the switch is open to heat the second portion of said vessel to a temperature above that of the first portion thereof.

9. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in limited heat exchange relationship primarily with the cooling unit, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel substantially solely during the period between the stopping and the starting of the flow of refrigerant to the cooling unit to maintain the temperature of the second portion of said vessel above that of the first portion thereof during said period.

10. In a mechanical refrigerator, the combination of an insulated cabinet, a cooling unit therefor, means for supplying refrigerant to said cooling unit, and a controlling device for said means comprising a vessel having a first portion thereof in heat exchange relationship primarily with the media in said cabinet and a second portion in limited heat exchange relationship primarily with the cooling unit, a volatile fluid in said vessel, said fluid being partially in the liquid phase, means responsive to the vapor pressure of said fluid for starting and stopping the flow of refrigerant from the refrigerant-supplying means to the cooling unit, and means for heating the second portion of the vessel by a heat source independent of the ambient air and of said refrigerant-supplying means.
